PACKAGE AND METHOD OF SEALING THE SAME

Filed Dec. 8, 1930

William M. Williams.

By: Charles Marshall Att.

UNITED STATES PATENT OFFICE

WILLIAM M. WILLIAMS, OF EVANSTON, ILLINOIS, ASSIGNOR TO B. F. GUMP COMPANY, OF CHICAGO, ILLINOIS, A CORPORATION OF ILLINOIS

PACKAGE AND METHOD OF SEALING THE SAME

Application filed December 8, 1930. Serial No. 500,723.

This invention relates to a package and method of sealing the same.

Retail stores usually receive certain commodities, such as coffee beans, for example, in paper bags. In instances, where it is the desire of the customer to have the coffee bean ground, the bag is opened, the coffee beans are ground and then replaced in the bag which has a metal clamping strip thereon for again closing the same. This metal clamping strip allows the bag to be readily opened so that a small portion of the contents could be taken out or stolen, and it frequently happened that the paper bags which were closed by a metal clamping strip were found to be under weight.

This invention seeks to overcome the objections above noted sealing the bags having the metal clamping strips, so that the seal may be broken when desired and the metal strip used for closing the bag.

The invention comprises the novel package and method hereinafter described and more particularly pointed out and defined in the appended claims.

In the accompanying drawing which illustrates a preferred form of the invention and in which similar reference numerals refer to similar features in the different views:

Fig. 1 is an elevational view of a package involving this invention;

Fig. 2 is an elevation of the upper portion of a paper bag with an attached metal clamping member;

Fig. 3 is a view similar to Fig. 2, illustrating the first fold in the neck of the bag;

Fig. 4 is a view illustrating the final fold in the neck of the bag;

Fig. 5 is a fragmentary part sectional and part elevational view illustrating certain features;

Fig. 6 is an elevational view of the upper portion of a bag having a modified form of metal closing strip;

Fig. 7 is a fragmentary part sectional and part elevational view of a bag containing the modified form of metal clamping

strip showing the manner of folding and sealing the neck thereof.

Referring now more particularly, to Figs. 1 to 5, there is shown a paper bag 1 with a paper flap 2 pasted or glued to one side. 55 This paper flap extends above the bag where it has laterally projecting portions 2a. The upper portion of the flap contains a pliable metal clamping strip; the flap being folded over the metal strip. 60

In the modified form of bag shown in Figs. 6 and 7, thin pliable strips of metal 3, vertically arranged are used. A suitable covering 4 such as paper or the like, is pasted or glued over the metal strip 3 to hold them 65 in place.

According to this invention, the neck of the bag is first collapsed and then folded over as shown in Fig. 3. It is then folded again as shown in Figs. 4 and 5, bringing the 70 metal clamping member beneath the fold as shown in Fig. 5. The neck of the bag in its folded position will assume the position shown in Figs. 4 and 5 over the center line 75 of the bag; the extensions 2a, however, projecting outwardly.

An adhesive tape 5 is then applied over the folded neck of the bag and over the ends of the bag. As this tape is applied, it will bend the extensions 2a down against 80 the ends of the bag as illustrated in Fig. 4 and will be glued thereover to seal the bag.

In the modified form shown in Figs. 6 and 7, the metal strips 3 are folded with the 85 neck of the bag and the adhesive tape is applied over the folded neck of the bag and against the ends thereof. In both forms the metal in the neck of the bag maintains the fold down while the tape is applied. 90

The tape 5 will securely seal the bags against being tampered with, and when such a package is received by a retail store and be desired to open a bag for treating the contents for a customer such as grinding 95 the same, he will merely tear the adhesive tape at the upper corners of the bag when the neck thereof may be unfolded and opened. After the contents have been treated and the same are returned to the 100

bag, the neck of the bag may be folded and the extensions folded or bent over the folded portion for closing the bag.

In the modified form, after the seal has 5 been broken, and the bag opened, it may again be closed by simply folding the neck of the bag, the metal strips 3 having sufficient rigidity to maintain the folded relations of the parts of the neck.

10 I am aware that many changes may be made, and numerous details of construction may be varied through a wide range without departing from the principles of this invention, and I therefore do not purpose 15 limiting the patent granted hereon, otherwise than necessitated by the prior art.

I claim as my invention:

1. A package having a folded neck portion, a metal member attached to the folded neck portion and bent over the body of the bag and a strip of adhesive tape glued over 70 the folded neck portion and over the body in superposed relation with said metal strip.

2. A package comprising a paper bag having a folded neck portion with a metal member extending longitudinally of said fold and beyond the ends thereof and a strip of adhesive tape glued longitudinally over 75 said folded neck portion and over the ends of said bag in superposed relation with said metal strip. 80
